JOSIAH OWEN SWISHER, OF JACKSONVILLE, FLORIDA.

BRICK-CLEANING MACHINE.

1,113,220.

Specification of Letters Patent.

Patented Oct. 13, 1914.

Application filed May 22, 1913. Serial No. 769,928.

To all whom it may concern:

Be it known that I, Josiah O. Swisher, a citizen of the United States, and a resident of Jacksonville, in the county of Duval and State of Florida, have made certain new and useful improvements in Brick-Cleaning Machines, of which the following is a specification.

My invention is an improvement in brick cleaning machines, and has for its object to provide a machine of the character specified, especially adapted for removing mortar and the like from bricks to prepare them for reuse, and having mechanism for thoroughly cleaning the entire surface of the brick, and for finally discharging the brick in condition to again be used.

In the drawings: Figure 1 is a front view of the machine, Fig. 2 is a view at right angles to Fig. 1, Fig. 3 is a top plan view, Figs. 4 and 8 are sections on the lines 4--4 and 8--8, respectively, of Fig. 1. Fig. 5 is an enlarged side view of one of the cleaning wheels, Figs. 6 and 7 are sections on the lines 6--6 and 7--7 respectively, of Fig. 5, and, Fig. 9 is a section on the line 9--9 of Fig. 4.

The present embodiment of the invention comprises a frame consisting of uprights 1, connected by longitudinal bars 2, and by cross bars 3. A driving shaft 4 is journaled at one end of the machine, in bearings 5 on the adjacent uprights, and the said shaft is provided near one end with a pulley 6, which may be connected to a suitable source 35 of power by means of a belt 7.

A shaft 8 is journaled in the bearings 9 on the uppermost bars 2, the said shaft being parallel with the shaft 4, and a third shaft 10 is journaled in bearings 11 on the lower bars 2, the said shaft 10 being directly below and parallel with the shaft 8, before mentioned. Pulleys 12 and 13 respectively are secured to the outer ends of the shafts 8 and 10, and belts 14 and 15 connect the respective pulleys 12 and 13 with pulleys 16 and 17 on the shaft 4.

The belt 15 which connects the pulleys 13 with the pulley 17 is outside the belt 14, and the shaft 10 is extended at the end adjacent to the pulley 13, to bring the said pulley out of register with the pulley 12, so that the

belts 14 and 15 may not interfere with each other. A feed board 18 is arranged at the front of the machine, the said feed board being supported by inclined braces 19, and the inner end of the said board is directly between the shafts 8 and 10.

A series of three shafts, 21, 21^a and 21^b is journaled on the upper cross bars 3 in bearing brackets 22 on the said cross bars, the said shafts being in parallel relation and in the same horizontal plane, and spaced apart at equal distances from each other. A second series of shafts 23, 23^a and 23^b is journaled in bearings 24 on the lower cross bars 3; the said shafts being in the same horizontal plane and parallel with each other, and arranged at equal distances, the spacing of the said series corresponding to the spacing of the series 21, 21^a and 21^b. The first-mentioned series of shafts is above the feed board 18, and the second series is just below the same. Pulleys 25 are secured to the shafts 21, 21^a and 21^b, at approximately their centers, the said pulleys being of equal size and in alinement, and other pulleys 26 are secured to the lower series at the centers thereof, and in alinement with each other and with the pulleys 25.

The inner edge of the feed board 18 is flush with the opposite ends of the pulleys 25 and 26 from the feed board, and the said feed board is provided with a lateral upstanding flange 20 at the said inner edge.

The shaft 21^a is provided with a sprocket wheel 29 at the end adjacent to the gear wheel, and the sprocket wheel is connected by a chain 30 with a sprocket wheel 31 on the adjacent end of a shaft 32 journaled parallel with the shaft 23^b and below the same. A bevel gear wheel 33 is arranged on the opposite end of the shaft 32 from the sprocket wheel 31, and the said bevel gear wheel meshes with a bevel pinion 34 on the drive shaft 4 before mentioned.

The bevel gear wheel 33 is journaled loosely on the shaft 32, and the hub 35 of the said wheel is provided at its inner end with one section of a clutch. The other section 36 of the clutch is feathered on the said shaft, and the said section is provided with an annular groove which is engaged by the

arms of a fork 37, on a lever 38, pivoted at 39 to a cross bar 40 inside the frame. By swinging the upper end of the lever 38 in the proper direction, the gear wheel 33 may be clutched to the shaft 32 or released therefrom, and the said shaft operates the shaft 21^b, which in turn drives the shaft 23^b. A cleaning wheel is secured on each of the shafts 8 and 10, and it will be noticed from an inspection of Fig. 1, that the said shafts 8 and 10 are in vertical alinement with the pulleys or rollers 25 and 26 on the upper and lower series of shafts. The pulleys or rollers 25 and 26 feed the brick through the machine, and the cleaning wheels above mentioned are arranged, between the shafts 21^a—23^a and 21^b—23^b. The wheel on the shaft 8 has its periphery at the lower part of the wheel between the pulleys or rollers 25 on the shafts 21^a and 21^b, and the lower cleaning wheel is similarly arranged with respect to the pulleys 26 on the shaft 23^a and 23^b, as to the upper part of the wheel.

Each of the said wheels 41 on the shaft 8 and 41^a on the shaft 10 is constructed as shown in Figs. 5 to 8 inclusive. Each wheel is composed of a pair of disks 42, 42^a, each disk having at its center a hub 43 for engaging the shaft 8 or 10 as the case may be, the hub being secured to the shaft by means of a set screw 44. Each of the said disks is provided at its periphery with an outwardly offset portion or flange 45, connected to the disk by an integral web 46.

35 The disks are arranged in spaced relation, as shown in Figs. 6 and 7, with a suitable filling 47 of cement, and when so arranged the flanges 45 on the said disks are spaced apart from each other to form an annular groove at the periphery of each wheel. The groove formed by the flanges 45 is filled by bristles 48, the said bristles being arranged in close relation and clamped between the flanges, by means of a series of bolts 48 and another series of bolts 49. The bristles are of wire or other stiff material, and the outer ends of the said bristles extend beyond the peripheries of the flanges 45.

50 Each wheel is in fact a brush of wire bristles, the said brush being arranged in circular form, and the shafts 8 and 10 are so arranged, and the wheels 41 and 41^a are of such size that they will engage the opposite faces of the brick passing between them, to thoroughly clean the same. At regular intervals blades 50 are secured to the flange 45 of the disk 42^a, each of the said blades extending radially of the wheel, and having its outer free end beveled, as indicated at 55 51. All of the blades are beveled in the same direction, and each blade is received in a recess 52 in the outer face of the flange 45, and one of the bolts 49 is passed through each blade, and the flanges 45 of the disks. 60 Nuts 53 engage the bolts on the opposite

side of the wheel, to hold the blades in place, and to assist in clamping the bristles between the flanges. The bolts 48 are engaged by nuts 54 and the series of bolts 48 is arranged nearer the peripheries of the flanges 45 than is the series 49. Countershafts 55 and 55^a are journaled in bearings 57^a on central uprights 1^a and in bearings 57 on the under faces of the central longitudinal bar 58, at right angles to the shafts 21 and 23. 70 The bar 58 connects the uppermost cross bar 3, and is arranged about midway between the longitudinal bars 2. The shaft 55 is provided with a pulley 59, and a belt 60 connects the said pulley with a pulley 61 on the driving shaft 4. A second pulley 62 on the shaft 55 is connected to a similar pulley 62^a on the shaft 55^a, by means of a belt 63. A second pair of countershafts 64 and 64^a is journaled below the shafts 55 and 55^a, in bearings 65 on the uprights 1, and in other bearings 66 in a longitudinal bar 67 arranged directly below the bar 58 above mentioned. The shaft 55 is in the same vertical plane with the shaft 64, and the shaft 55^a is in the same vertical plane with the shaft 64^a. Each of the shafts 55 and 64 is provided with a wheel or pulley 68, and the said wheels or pulleys are in register and are connected by an endless belt 69, provided on its outer face with radial bristles 75 79 of wire or the like.

Each of the shafts 55^a and 64^a is provided with a wheel 68^a, the said wheels being in register, and being also in register with the wheels 68 of the shafts 55 and 64. An endless belt 69^a provided with radial brushes 70^a of wire or the like, is supported on the wheels or pulley 68^a, and the adjacent runs of the said belts move in opposite direction 105 and are spaced apart a sufficient distance to engage the side edges of a brick to thoroughly clean the same, as it moves between the said runs.

In operation, the bricks are fed from the feed board 18. The bricks 71 are arranged in succession against the flange 20 of the feed board, and with their long axis perpendicular to the shafts 21 and 23. As the bricks are pressed toward the said shafts, 110 their upper and lower faces are engaged between the rollers of the shafts 21^b and 23^b, and are carried transversely of the machine. The shafts of each series 21—21^a—21^b, and 23—23^a and 23^b are spaced apart such that 115 the wheels or rollers of shafts 21^a and 23^a will engage a brick before it has passed between the wheels or rollers on shafts 21^b and 23^b, as shown in Fig. 2. The bricks will thus be fed continuously transversely of the 120 said shafts. As the bricks move from between the shafts 21^b and 23^b, their upper and lower faces are engaged by the wheels 41 and 41^a, the said wheels rotating in the same direction, so that the adjacent portions of 125 130

their peripheries are moving in opposite direction. Thus there is no tendency to sweep the brick laterally, and the upper and lower surfaces are thoroughly cleansed by the wire bristles.

3 The blades 50 have the points thereof near to the extremities of the bristles, as will be evident from an inspection of Figs. 5 and 6, and the said belts will remove adhering 10 bits of mortar too firm for removal by the bristles. As the bricks pass from between the rollers or shafts 21^a and 23^a, the side edges are engaged by the bristles 79 of the endless belts 69 and 69^a. The bricks are fed 15 continuously with the front end of each brick in contact with the rear end of the preceding brick, and they are finally discharged through the machine at the rear end thereof thoroughly cleansed and in shape 20 for relaying.

By means of the lever 38, the feeding mechanism for the bricks may be disconnected from the operating mechanism of the wheels 41—41^a and the belts 69—69^a, to permit 25 the movement of the bricks to be checked, when it is desired to submit any particular brick to the action of the cleaning devices for a longer time than usual. The shafts 21—21^a and 23—23^a are operated by the 30 movement of the bricks, which are pushed rearwardly, by the shafts 21^b—23^b.

It will be noticed from an inspection of Fig. 9, that the hub 35 of the gear wheel 33 is a socket engaging the end of the shaft 32. 35 The socket is held in its bearing 72, by means of collars 73 arranged on opposite sides of the bearings, and held to the hub by set screws 74. The bearing 72 depends from the cross bar 40 and the lever 38 is pivoted 40 to the bracket arm 75 extending laterally from the said cross bar, by means of a pin 39. The movable clutch section 36 is constrained to rotate with the shaft 32 by means of a feather 77 which engages a 45 groove in the bore of the clutch section.

A loose pulley 6^a is arranged on the shaft 4 adjacent to the pulley 6, and when necessary or desirable, the belt 7 may be shifted to the loose pulley 6^a, to stop the operation 50 of the brick cleaning machine without stopping the motor. It will be noted from an inspection of the drawings, that a gear wheel 78 is secured to the shaft 21^a, and that the said gear wheel meshes with gear wheels 55 79 and 80 on the shafts 23 and 23^a. Thus the shafts 21^a, 23 and 23^a are positively rotated, the arrangement being such that one feed roller of each vertical pair is positively driven.

60 The arrangement of the wire bristles on the belts is such that a coarse wire is used at the front edge of the said belts, while those at the rear edge are fine, and the wires gradually decrease from coarse to fine, so 65 that the brick is first engaged by the coarse

wires and last is engaged by the fine wires. The coarse wires loosen the mortar while the fine wires clean it completely.

I claim:

1. A machine of the character specified, 70 comprising a supporting frame, a plurality of series of shafts arranged transversely of the frame, the shafts of each series being in the same horizontal plane and arranged in spaced relation, and one of the said series being arranged directly above the other series, and in spaced relation, each shaft of each series being in vertical alignment with the adjacent shaft of the other series, feed rollers journaled on the shafts of each series, said rollers being in alignment transversely of the machine and being arranged in such relation that the rollers of the succeeding pair of shafts will grasp a brick before it is released by the rollers of the preceding pair of shafts, a support for the brick in front of the machine and at the first pair of rollers, shafts journaled above and below the said series and at right angles thereto, a cleaning wheel on each shaft, one 80 of the said wheels having the lower portion of its periphery extending between the first and the second feed roller of the upper series and the other wheel having the upper portion of its periphery extending between the first and second roller on the lower series, each of the said cleaning wheels having an annular groove in its periphery, said grooves being filled with wire bristles, the 85 free ends of the bristles extending beyond the wheels for engaging the brick to clean the same, radial blades secured to each wheel at the front side thereof and extending beyond the periphery of the wheel, said blades being arranged in spaced relation, the 90 wheels engaging the upper and lower faces of the brick, endless cleaning belts mounted on each side of the feed rollers between the last and the next to the last feed rollers, said belts being arranged with their adjacent 95 runs parallel and in spaced relation, each run having laterally extending wire bristles on its outer face for engaging the sides of the brick, means for rotating the cleaning wheels in the same direction, means for moving the belts with their adjacent runs moving in opposite directions, a driving connection between the feed shafts at the front of the machine, means for rotating one of the 100 said shafts, and means for disconnecting 105 said shaft to and from its rotating means.

2. A machine of the character specified, comprising a supporting frame, cleaning wheels arranged one above the other and with the adjacent portion of their peripheries in spaced relation, wire bristles in connection with each wheel and extending beyond the periphery thereof, cleaning belts provided with laterally extending bristles, 110 said belts being arranged behind the clean- 115

ing wheels and mounted for vertical movement with their adjacent runs parallel and in spaced relation, each of the cleaning wheels having radial cleaning blades arranged in spaced relation and extending beyond its periphery, and means for feeding a brick between the wheels and the adjacent runs of the belts, said means comprising upper and lower series of horizontal 5 shafts arranged in the same plane and spaced apart from each other, the shafts of the upper series registering with the shafts of the lower series, a feed roller on each shaft, said rollers being in alinement and the rollers of the upper series being spaced apart from the rollers of the lower series 10 to receive a brick between the same, the rollers of the series being spaced apart to permit each roller to grasp the brick before the succeeding roller releases the same, driving mechanism, a driving shaft for the machine, connections between the said driving shaft, the wheels and the belts for operating the same, and means for connecting and disconnecting the shafts and the driving 15 shaft.

3. A machine of the character specified, comprising a supporting frame, cleaning wheels arranged one above the other and with the adjacent portion of their peripheries in spaced relation, wire bristles in connection with each wheel and extending beyond the periphery thereof, cleaning belts provided with laterally extending bristles, 20 said belts being arranged behind the cleaning wheels and mounted for vertical movement with their adjacent runs parallel and in spaced relation, each of the cleaning wheels having radial cleaning blades arranged in spaced relation and extending beyond its periphery, and means for feeding a brick between the wheels and the adjacent runs of the belts, and means for operating the belts and the cleaning wheels. 25

4. In a machine of the character specified, a pair of cleaning wheels mounted to rotate on parallel axes in vertical alinement, wire bristles on the peripheral surface of each wheel, the free ends of the bristles extending 30 beyond the said surface, a series of cleaning blades secured to the front face of each wheel and extending beyond the periphery thereof, said blades being arranged in spaced relation, each blade having its free end beveled, the wheels being spaced to engage the upper and lower faces of the brick, 35 means for rotating the cleaning wheels and means for feeding a brick between the wheels. 40

5. In a machine of the character specified, a cleaning wheel comprising a pair of disks each having a hub at its center for receiving a shaft, each of the said disks having a laterally outward offset annular flange at 45 its periphery, bristles of wire clamped be-

tween the flanges of the disks and with their free ends extending beyond the periphery of the disks, means for clamping the disks together on the bristles, and radial blades secured to the flange of one disk and extending beyond the periphery thereof, each blade having its outer end beveled, said bristles extending beyond the blades. 50

6. In a machine of the character specified, a cleaning wheel provided with an annular 70 peripheral groove, wire bristles in the groove extending beyond the periphery of the wheel, means for holding the bristles in the groove, and radial blades arranged in spaced relation at the periphery of each 75 wheel on one face thereof, said blades extending beyond the periphery of the wheel and each blade having its free end beveled.

7. In a machine of the character specified, a cleaning wheel provided with an annular 80 peripheral groove, wire bristles in the groove extending beyond the periphery of the wheel, means for holding the bristles in the groove, and radial blades arranged in spaced relation at the periphery of each 85 wheel on one face thereof.

8. In a machine of the character specified, a cleaning wheel provided with an annular 90 peripheral groove, wire bristles in the groove extending beyond the periphery of the wheel, and cleaning blades at the periphery of the wheel. 95

9. In a machine of the character specified, means for cleaning the opposite sides of the brick, the said means comprising pairs of 100 shafts arranged in vertical spaced relation, wheels on the shafts, the said wheels of each pair of shafts being in alinement and in alinement with the wheels of the other pair of shafts, an endless belt supported on each 105 pair of wheels, each belt having laterally extending wire bristles, means for rotating the belts with their adjacent runs moving in opposite directions, and means for feeding brick between the belts. 110

10. In a machine of the character specified, a cleaning device for bricks comprising oppositely arranged endless belts, means for supporting each of the said belts for longitudinal movement and with their adjacent 115 runs moving vertically and in opposite directions, each belt having a plurality of wire bristles on its outer face for the purpose specified, and means for operating the belt.

11. In a machine of the character specified, means for cleaning opposite faces of the brick, said means being arranged in spaced relation, means for cleaning the opposite side edges of the brick, said means being arranged in spaced relation to permit the 120 passage of a brick between the same and in rear of the first named cleaning means, and means for feeding the brick past the said cleaning means, said feeding means comprising upper and lower series of horizontally 125 130

arranged shafts, the shafts of each series being in the same horizontal plane and spaced apart from each other a distance less than the length of the brick to be fed, the 5 shafts of the lower series being in vertical alinement with the shafts of the upper series, and rollers on the shafts, said rollers being in transverse alinement and adapted to grasp the opposite faces of the brick to move the same, means for operating sundry 10 of the rollers, and means for releasing the said rollers at will from the operating means.

JOSIAH OWEN SWISHER.
